CIGARETTE EJECTOR HOLDER

Arnold Silverman, New York, N. Y.

Application August 16, 1948, Serial No. 44,558

5 Claims. (Cl. 131—182)

This invention relates to cigarette holders and, more particularly, of the type having an ejector for facilitating the removal of the cigarette butt from the holder.

The object of the invention is to provide a holder which has means for gripping the inserted end of a cigarette in a firm and positive manner without unnecessarily compressing or piercing the cigarette or adversely affecting its smoking qualities. This positive grip is achieved by a plurality of split elements which are caused by movement, to engage the inserted portion of the cigarette paper within these elements which, in the engaged position, form a cylindrical bore with an inside diameter such as to maintain substantially the periphery of the cigarette and, at the same time, these said elements in assuming this engaging position, will engage the outer surface of the cigarette paper and at substantially all of the slits crimp the cigarette paper between their edges. As evidence that these improved plurality of split elements of this invention do exert this manner of grip upon the cigarette paper, the cigarette after being locked or gripped in the improved holder will upon inspection reveal a plurality of parallel minute crimps distinctly formed in the paper.

Cigarette holders have been proposed heretofore which involve various types of gripping members that either compress, pierce, or otherwise hold the cigarette. But none of these combines with such engaging grip upon the inserted end portion, the improved plurality of split elements, as more particularly described herein, which crimp or pleat the cigarette paper to assure a positive grip and make the cigarette captive thereby.

By gripping the cigarette paper in the manner described, not only is the cigarette more firmly held in the holder, but the inserted portion of the cigarette is not compressed to any appreciable extent, nor is the tobacco appreciably compacted or the end of the cigarette, particularly the paper end appreciably fouled or crushed as occurs in many types of split or pierced holders.

An allied object is to provide the aforementioned, improved plurality of gripping split members in a cigarette holder of the ejector type.

For the attainment of the foregoing and such other objects as may appear or be pointed out herein I have shown an embodiment of my invention in the accompanying drawing, wherein:

Fig. 1 is an elevation view of the improved holder in cigarette holding position;

Fig. 2 is a section (on a scale enlarged over that of Fig. 1) of the forward operative portion of the holder;

Fig. 3 is a cross section through the multi-crimp gripping split elements at the end of the holder and through the cigarette held therein, taken on a somewhat larger scale, on the line 3—3 of Fig. 2.

Fig. 4 is a longitudinal section, similar to Fig. 2, but showing the parts in butt-ejecting position.

The improved cigarette holder of this invention, shown complete in Fig. 1, comprises a mouthpiece or bit 9 (which may, if desired, be implemented with a filter)

2

having a central smoke bore 8, Fig. 2, and a reduced portion 5, at the end of which the smoke bore 8 terminates in an enlarged mouth 7 which is tapped to receive the threaded nipple 17 of ejector pin 19, which also has a central smoke bore 18. The outside diameter of ejector pin 19 is less than the outside diameter of the reduced portion 5 of the bit 9, to provide an annular space for a helical spring 6. The spring is completely concealed by, and contained within the overlapping end portion 25 of a partially split tube 20. The partially split tube 20, or rather its overlapping and unsplit rear end portion 25, is slidably mounted on the reduced portion 5 of the bit and is limited in its movement toward the bit 9 by the compression of spring 6 between the annular shoulder 26 and the forward end of the reduced portion 5 of the bit 9. To limit its forward movement, the partially split tube 20 has an inner annular shoulder 26 which is abuttable, when the partially split tube 20 is positioned forwardly against the enlarged head 16 of ejector pin 19. The aforesaid helical spring 6 is interposed between the forward end of the bit 9 and the said inner shoulder 26 of the partially split tube 20, so that this compression spring 6 normally urges the partially split tube 20 outwardly or forwardly, to the position shown in Fig. 2.

The rear portion 25 of the partially split tube 20 is solid annularly; the forward portion thereof is divided into a plurality of narrow slits or cuts 29 into a plurality of elements 28. Said slitting cuts 29 extend rearwardly from the forward end of the tube to a point at the rear of the annular shoulder 26. Said slits may stop at the annular shoulder or, they may continue through and divide the annular shoulder as shown in Fig. 2. This is entirely optional and depends upon the choice of materials used in construction, what operative resistance is desired, and other factors.

Partially split tube 20 is fabricated of resilient material in a manner to cause the forward elements or fingers 28 to assume their normal free position when expanded outwardly, as in Fig. 4, and when under no restraint, in the butt ejecting position. The word restraint, as used herein, is intended to describe the condition when the slide sleeve 30 encircles the partially split portion 25 of tube 20; the inside diameter of sleeve 30 being such as to permit travel over the annular solid portion 25 of the partially split tube 20. That is, the slide sleeve 30 travels quite readily over the annular solid portion 25, but meets resistance when it is moved forwardly over the elements or fingers 28 of tube 20 and compresses them into closed position. As mentioned above, partially split tube 20 is of resilient stock and formed so that its elements or fingers 28 tend to spread outwardly, as shown in Fig. 4. That is, when the slide sleeve 30 is positioned adjacent to the annularly solid portion of partially split tube 20, and is slid up to stop 24 of said tube, also up to stop 4 of bit 9, all as shown in Fig. 4, no restraint is imposed on the elements or fingers 28 and they expand in a radially outward direction so that a series of predetermined open spaces are developed between the elements or fingers 28.

Slide sleeve 30 may have one or more rings 31 or protuberances or other gripping means to facilitate moving it relative to partially split tube 20. To limit this movement, the forward (rightward, Figs. 1, 2, 3) end of the elements 28 have enlargements 27 which are abutted by the forward end of sleeve 30, as in Fig. 2. The left or rear end 24 of partially split tube 20 has an annular rib or flange which is abutted by the corresponding or left end of the slide sleeve 30, to limit movement in this direction.

The improved holder is prepared for reception of a cigarette by moving the slide sleeve leftwardly, toward

and back to stop 24, said movement freeing the multi-split elements so that they may spring outwardly, as in Fig. 4, and present a flared opening into which the end of the cigarette may be freely inserted. The extent of insertion of the cigarette is predetermined by the abutment of the end of the cigarette with the ejector head 16. It should be noted that when the slideable sleeve 30 is in this retracted position to about 24, the expansive movement of the split spring elements 28 produces two results:

(a) The inside diameter of the split portion of tube 20 is enlarged so that a cigarette may be easily inserted therein, and

(b) The spaces 29x of Fig. 4, between the spring elements are now at their predetermined maximum.

When the slideable sleeve 30 is advanced rightwardly to about the stops 27, as in Fig. 2, the multi-split elements 28 are brought to their restrained position in which they approach one another to form a cylindrical encirclement about the inserted portion of the cigarette, Figs. 2 and 3. Additionally, and particularly the elements or fingers 28 in approaching one another reduce the spaces between them from that shown at 29x (Fig. 4) in open, flared-out position to that shown at 29 (Fig. 2, and Fig. 3) in closed, restrained, cylindrical position. This closing movement of the elements generally crimps the cigarette paper at a, Fig. 3, between the co-operative edges of the fingers as the true periphery of the cigarette is slightly reduced to allow for the forming of distinct multi-folds or crimps therein, as at b, Fig. 3.

The engagement of these crimped portions of the cigarette paper between these split elements 28 results in a positive grip upon the cigarette paper making the cigarette captive in the cigarette holder, all as herein and previously pointed out.

To eject the cigarette or the smoked butt, the slideable member 30 is moved leftwardly, Fig. 4, to cause its left end to abut left flange 24 of the partially split tube 20; this movement of sleeve 30 sets free the split elements 28 which spring outwardly, Fig. 4. Continued leftward movement of slideable sleeve 30 draws the partially split tube with said sleeve until it is stopped by the abutment 4, but not the cigarette itself, because of the cigarette's abutment, as aforesaid, with ejector head 16. The result is such that the elements 28 first act to release the cigarette paper by the opening up of the crimping elements, said elements then being withdrawn leftwardly in their entirety from the cigarette butt which is progressively freed and ejected. This leftward movement of the parts is limited by said abutment of flange 24 of the partially split tube 20 with shoulder 4 of the bit 9, as shown in Fig. 4. As a result of this leftward movement, spring 6 is compressed, see Fig. 4, so that upon release of the slideable sleeve 30, the partially split tube 20, together with sleeve 30 occupying the annular solid portion 25 thereof, will be returned to their normal positions, ready to receive another cigarette as described above.

It will be observed that the split elements or fingers 28 spring or flare outwardly due to their inherent resiliency, so that the sleeve 30 operates on the outer surface of the elements to cause them to approach one another to form a cylindrical encirclement.

I claim:

1. In a holder for cigarettes, in combination, a bit having a reduced forward end portion, an ejector pin of less diameter than said reduced portion, secured to the bit and having an enlarged head at its forward end, a tube slidably mounted on said reduced portion of the bit and having its forward end portion longitudinally slit into a plurality of elements and provided with an internal shoulder disposed between said enlarged head of the ejector pin and said bit so that said tube is slidably secured in place, a sleeve slidable on said tube, the split portions of the split tube having flared end enlargements to limit the movement of said sleeve, said tube being fabricated of resilient material and formed so that when said sleeve

is moved to free said elements, said elements flare outwardly to freely receive the end portion of a cigarette and to provide predeterminedly maximum spaces between their edges; movement of said sleeve toward the split end causing the elements to approach one another to encircle said cigarette portion and causing the cigarette paper caught in said predeterminedly maximum spaces to be crimped thereby to positively grip the cigarette; movement of said sleeve toward said bit causing the tube to move in the direction of said bit, the cigarette being prevented from following by said ejector pin, whereby the said outwardly flared elements are withdrawn from said cigarette portion to free the cigarette, and a compression helical spring disposed between the end of said bit and said internal shoulder of the tube for returning the tube in position for receiving a cigarette, movements of said tube being limited by said compression spring against one end of said reduced portion and said enlarged head of the ejector tube.

2. In a holder for cigarettes, in combination, a bit having a forward reduced portion terminating in an ejector head, a tube slidably mounted for limited movement on said reduced portion and having its forward end portion longitudinally split into a plurality of elements, a sleeve slidably mounted for limited movement on said split tube, said split tube being fabricated of resilient material and formed so that when said sleeve is moved toward said bit to free said elements, said elements flare outwardly to freely receive the end portion of a cigarette and to provide predeterminedly maximum spaces between their edges; movement of said sleeve toward the split end causing the elements to approach one another to encircle said cigarette portion and causing the cigarette paper caught in said predeterminedly maximum spaces to be crimped thereby to positively grip the cigarette further movement of said sleeve moving the split tube in the direction of said bit, the cigarette being prevented from following by said ejector head, whereby the outwardly flared elements are withdrawn from said cigarette portion to free the cigarette, and a compression helical spring disposed in said reduced portion for returning the split tube forwardly in position for receiving a cigarette.

3. In a holder for cigarettes, in combination, a bit having a forward reduced portion terminating in an ejector head, a tube slidably mounted for limited movement on said reduced portion and having its forward portion longitudinally split into a plurality of elements, a sleeve slidably mounted for limited movement on said split tube, said split tube being fabricated of resilient material and formed so that when said sleeve is moved toward said bit to free said elements, said elements flare outwardly to freely receive the end portion of a cigarette and to provide predeterminedly maximum spaces between their edges; movement of sleeve toward the split end causing the elements to approach one another to encircle said cigarette portion and causing the cigarette paper caught in said predeterminedly maximum spaces to be crimped thereby to positively grip the cigarette further movement of said sleeve moving the split tube in the direction of said bit, the cigarette being prevented from following by said ejector head, whereby the outwardly flared elements are withdrawn from said cigarette portion to free the cigarette.

4. In a holder for cigarettes, in combination, a bit, a split tube slidably mounted for limited movement on said bit and having a plurality of spring elements at its forward end portion, a sleeve slidably mounted for limited movement on said split tube, said sleeve being operative to move said tube toward said bit for moving said elements outwardly to freely receive the end portion of a cigarette and to provide predeterminedly maximum spaces between their edges; movement of said sleeve toward the forward end on the tube causing the said elements to approach one another to cause the cigarette paper caught in said spaces to be crimped thereby to positively grip the cigarette.

5. In a cigarette holder of the type including a mouthpiece, a mouthpiece base extension and a cigarette holder extension, said cigarette holder extension comprising a tube having at its forward end a plurality of spaced fingers, and a sleeve slidably mounted on said cigarette holder extension, said holder extension being of resilient material and arranged in one position with the fingers flared outwardly to provide slots therebetween, and in another position with its fingers in parallel spaced relation, said sleeve when moved toward its forward end on 10 said holder causing said spring fingers to approach one another, to crimp and grip portions of the wrapper of a cigarette positioned in the cigarette holder extension.
